FUEL CUT-OFF DEVICE FOR FUEL INJECTION SYSTEM

Elmer Olson, Ellsworth A. Kehoe, and Lawrence C. Dermond, Rochester, N.Y., assignors to General Motors Corporation, Detroit, Mich., a corporation of Delaware

Application March 25, 1957, Serial No. 648,300

6 Claims. (Cl. 123—119)

The present device relates to a fuel control device for a fuel injection system and more particularly a device in which fuel flow to the engine's cylinders is interrupted during certain decelerating conditions.

Deceleration fuel cut-off devices are well known but such devices particularly as applied to fuel injection systems have for various reasons not functioned satisfactorily. Fuel cut-off devices which have utilized manifold vacuum as a fuel flow interrupting control force, as shown in Serial No. 608,797, filed September 10, 1956, have been particularly trouble-some in practical applications. Manifold vacuum type fuel cut-off devices are designed to interrupt the fuel flow when the manifold vacuum reaches a given value indicative of deceleration. With the engine idling, as when in neutral, and the throttle suddenly opened then closed, the manifold vacuum will usually equal or exceed the value required to shut off the flow of fuel with the result that the engine will stall. This same type of thing occurs when shifting a synchromesh type transmission through the various gear ratios, in this case, when the engine is accelerating and then the clutch depressed to change gear ratios, the vacuum rises rapidly due to release of engine load causing the engine to tend to stall. In the fuel cut-off mechanism is set to function at a sufficiently high manifold vacuum level to avoid the neutral kick or ratio change stalling, as described, the fuel cut-off mechanism will be ineffective to cut off fuel flow below relatively high vehicle speeds. To illustrate, a normal deceleration fuel cut-off device might be designed to operate on twenty inches of vacuum. During the neutral throttle kick as described, manifold vacuum might easily go to twenty-three inches of vacuum actuating the fuel cut-off device to stall the engine. Essentially, the same phenomena would occur in changing gear ratios. If this situation was corrected by setting the fuel cut-off device to function at some value above twenty-three inches, the fuel cut-off function would be absent under 40 to 45 miles per hour vehicle speed since under these speeds manifold vacuum would not be likely to reach or exceed twenty-three inches of vacuum. Other devices have been utilized to delay the actuation of the vacuum operated fuel cut-off devices but these additions have made the operation of the fuel cut-off mechanism too slow to give satisfactory operation.

The present device avoids the above difficulty by using a solenoid controlled fuel cut-off valve in conjunction with series connected throttle and engine speed control switches such that with the throttle closed and the engine operating above a given speed, the solenoid valve will cut off the fuel supplied to the engine cylinder. Below a given engine speed or with the throttle switch open the solenoid valve will be rendered inoperative to restrict fuel flow.

In addition to the novel combination of speed and throttle switches in controlling fuel injection fuel flow, a unique type of solenoid actuated valve is provided.

Other advantages and objects of the present invention

2

will be apparent from a perusal of the detailed description which follows.

In the drawings:

Figure 1 is a diagrammatic representation of a fuel injection system embodying the subject deceleration fuel cut-off device; and

Figures 2 and 3 are enlarged views of the solenoid control valve.

In the diagrammatic representation of Figure 1, a fuel induction passage is shown generally at 12 and includes a venturi 14 posterior of which is a throttle valve 16. A fuel supply source is indicated generally at 18 and includes a float controlled type valve mechanism 20, an engine speed responsive pump 22 and a fuel metering valve generally indicated at 24. The metering valve is under the control of a diaphragm 26 through a linkage mechanism 28. The preceding elements and devices function in the same manner as described in copending application 646,081, filed March 14, 1957 by L. C. Derwood. It will suffice to note that fuel is supplied to the metering valve 24 by pump 22 under a pressure which is proportional to engine speed. Valve 24 then delivers fuel to a distributor supply line 30 in accordance with the actuation of the control mechanism 26—28 which primarily is under the control of vacuum in passages 32 and 34. The vacuum in passage 32 is proportional to the mass of air flowing through the induction passage 12 and hence causes diaphragm 26 to move valve 24 to a position increasing the flow of fuel to line 30 as said mass air flow increases. Manifold vacuum is available in conduit 34 when the throttle 16 is closed as described in copending application Serial No. 608,797 Olson, filed September 10, 1956.

An idle air bypass network is indicated generally at 44 and includes a passage 46 communicating with the induction passage anterior of throttle 16, a passage 48 communicating with the induction passage posteriorly of the throttle and a passage 50 interconnecting passages 46 and 48. Normally a manually adjustable valve is disposed in such network and which valve is adjusted for an average idle air flow. It is apparent that such average adjustment of a manual valve is necessarily a comprise setting and is neither correct when the engine is hot nor when it is cold. Further, such a manual valve usually requires frequent adjustment due to normal engine operation. In the present device a thermostatically controlled valve 52 is interposed in passage 50 and is adapted to accurately control the idle air flow in accordance with the varying requirements of the engine as determined by engine temperature. In order that the temperature responsive valve accurately reflect engine temperature, a housing 54, within which the thermostatically controlled valve 52 is disposed, is mounted upon the engine cooling system as described in copending application 650,389, filed April 3, 1957 and now Patent No. 2,848,986. A thermostat 58 is mounted in housing 54 and fixed at one end 60 to the housing and at the other end to the valve shaft 62. In order to provide an initial cold running setting for the valve 52 an adjusting screw 64 is provided which acts through a lever 66 fixed to shaft 62.

As shown in Figure 1 with the engine cold, valve 52 will be in its maximum open position as determined by screw 64 permitting the maximum quantity of air to be bypassed around throttle valve 16 insuring sufficient air to provide faster than normal engine idling speeds under cold conditions. Through this device the normal fast idle cam, which sets the throttle idling position in accordance with engine temperatures, is eliminated. Accordingly, under idling conditions the throttle may always be closed with the variations in the quantity of the idling mixture being controlled in the idle air bypass network as described.

To secure adequate fuel enrichment when the engine is running cold additional means are provided to supplement the normal venturi vacuum signal acting on the upper side of metering valve control diaphragm 26.

Devices which have been used heretofore to insure an enriched starting mixture have been unsatisfactory from economy and performance standpoints since they are active to the same extent irregardless of engine temperature. The result of this type of temperature insensitive operation is to supply an overly enriched starting mixture to a partially warm engine wasting fuel and making engine performance sluggish. To eliminate this problem, the present device provides vacuum boost signals which are modulated in accordance with engine temperature and which thus preclude overenrichment of the starting mixture since the latter is always keyed to engine temperature.

In order to provide a metering diaphragm modulating signal a conduit 70 connects the metering diaphragm to a point posterior to the throttle 16. In the diagrammatic disclosure of Figure 1 a branch 71 of conduit 70 connects with idle air bypass passage 48, which as noted, connects with the induction passage 12 posteriorly of the throttle 16. A first valve device 72 is disposed in conduit 70 for controlling the amount of manifold vacuum transmitted to the diaphragm 26. Valve device 72 includes a member 74 slidably disposed in casing 76 and which member is suitably articulated to the thermostatically controlled lever 66. Thus, when the engine is cold the valve will be in the position shown in Figure 1 transmitting the maximum amount of manifold vacuum available in line 71 to the diaphragm 26. As the engine warms lever 66 will rotate in a counterclockwise direction moving the member 74 to a position modulating or gradually cutting off the amount of manifold vacuum superimposed on the diaphragm 26. Device 72 modulates the vacuum force by providing the member 74 with a suitably tapered portion 78 disposed between lands 80 and 82. Land 80 has a passage 84 therethrough for transmitting the vacuum force to diaphragm 26. If desired, passage 84 may be utilized to reduce the vacuum force available to act on the diaphragm and in this way serve as an orifice in line 70.

An additional valve device 90, in parallel with valve 72, is disposed in the manifold vacuum circuit and is adapted to provide additional manifold vacuum during the cranking operation of the engine under which condition a particularly rich starting mixture is desired. Device 90 likewise includes a member 92 slidably disposed within casing 94 and which also includes a tapered section 96 for metering the manifold vacuum flow to the diaphragm in inverse proportion to engine temperature. Valve device 90 also has associated in series therewith a ball check valve 100 which upon the starting of the engine is adapted to cut off the manifold vacuum flow through the branch circuit 102. Thus during cranking of the engine valve devices 72 and 90 are each transmitting a manifold vacuum force to the diaphragm 26. As soon as the engine begins to run, however, the cranking modulating signal is cut off and manifold vacuum modulation takes place only through valve 72.

In the event a warm engine is re-started the sliding members 74 and 92 will be in a position to modulate the manifold vacuum to supplement venturi vacuum or to eliminate the manifold vacuum force entirely dependent on the residual engine warmth. The valve devices 72 and 90 are shown in their cold running positions. As noted with increasing engine temperatures the sliding members 74 and 92 are gradually shifted to the left, as viewed in Figure 1, by thermostatically controlled lever 66 to reduce and ultimately eliminate the force of manifold vacuum on diaphragm 26.

In order to cut off the flow of fuel in the cylinder fuel supplying conduit 30 under certain decelerating conditions a fuel cut-off device indicated generally at 110 is provided. This device includes a solenoid actuated valve

member 112 disposed on top of a fuel distributing manifold or spider 114. As best seen in Figure 2 the fuel manifold comprises a casing having a boss 116 depending therefrom and to which is suitably connected fuel conduit 30. The manifold casing 114 also includes a plurality of circumferentially spaced radial bosses 118 each of which is connected to a fuel line 120 leading to an individual cylinder of the engine. Under normal operating conditions the metered fuel from valve 24 enters the fuel manifold through boss 116 and is equally distributed to all of the cylinders of the engine. Fuel inlet passage 122 communicates with a central passage or chamber 124 in communication with radial passages 126 leading to the cylinder supply lines 120.

15 The solenoid 112 includes an armature 130 axially slidable within the coil 132 and projecting from the end of which is a valve member 134 having a tapered end 136 adapted to cooperate with fuel inlet passage 122 to cut off the flow of fuel to chamber 124 when the solenoid 20 is actuated to move the solenoid downwardly. Under normal conditions the armature 130 is retained in its upper position so as to move the metering valve 134 out of flow restricting engagement with fuel passage 122. While armature 130 may be held in its upper or normal 25 restricting position by means such as a spring, the present device avoids the necessity of such means and instead utilizes the pressure of fuel in passages 122 and 124 which acts against the tapered end 136 of the valve as well as the tapered surface 140 of the armature to retain the latter in its retracted position. It is apparent that by using fluid pressure to retract the armature a simplified and cheaper type structure results.

The solenoid 112 is actually mounted on manifold 114 by a plurality of studs 142 which extend through the manifold intermediate radial passages 126. Studs 142 thread in openings 144 in a lower end plate 146 which is peripherally relieved at 148 to provide an annular lip 150. Solenoid casing 152 is bent radially inwardly at its respective ends to clampingly engage end plates 146 and 154. Lower end plate 146 includes an upstanding boss 156 tightly surrounding which is an armature supporting sleeve 158. Sleeve 158 projects through end cap 154 and is enclosed by a fluid tight cover 160. The end 162 of boss 156 is tapered to correspond to the tapered end 140 of armature 130.

35 End plate 146 is centrally relieved at 164 to receive a boss 166 formed on fuel manifold 114. An annular recess 168 surrounds boss 166 and receives a seal 170 to prevent the leakage of fuel between the solenoid and fuel manifold.

40 The control of solenoid valve 130—134 is through the combined effects of a throttle controlled switch 172 and a switch 174 responsive to the speed of the engine. Switches 172, 174 and solenoid 112 are in series with a 45 source of power 176, such as the vehicle battery.

45 The throttle controlled switch 172 may be of any convenient type and inasmuch as it does not, per se, constitute the subject matter of the present invention, is not shown in detail. The essential requirement of switch 50 172 is that it be closed only when the throttle is closed as will be the case when the engine is decelerating under conditions wasteful of fuel. Unless, however, means were provided to correct therefore the provision of a throttle controlled switch only for actuating the solenoid 55 112 would result in frequent engine stalling since the throttle might remain closed until the engine had passed well below the speed where fuel was passing unburned through the engine. To avoid this situation the additional switch 174 is provided and which switch is adapted to be closed above a certain engine speed. Here again, the engine speed responsive switch mechanism 174 is not shown in detail since any well known type of speed switch may be utilized to perform the intended function. For instance, switch 174 may be operated by a fly-ball 60 governor, generator voltage, etc.

Engine speed switch 174 may be adjusted to open at speeds below 30 miles per hour interrupting the flow of current to the solenoid 112 irregardless of the fact that the throttle control switch 172 might be closed and thereby insuring that the fuel cut-off mechanism will function no longer than necessary.

Power source 176 is connected to the speed control switch 174 through a lead 178, the speed switch to the throttle control switch through a lead 180 and the throttle control switch to the solenoid controlled valve through a lead 182 with the solenoid being grounded through lead 184.

The operation of the deceleration cut-off device is briefly as follows: with the throttle valve 16 closed and the engine operating above a given minimum speed the solenoid valve 112 will interrupt the flow of fuel from the fuel manifold 114 until such time as the throttle is again opened or the engine speed drops below a given value as described.

We claim:

1. A fuel injection system for an internal combustion engine comprising an air induction passage, a venturi formed in said passage, a throttle valve in said induction passage posterior to said venturi, a source of fuel under pressure, conduit means communicating said fuel source with the cylinders of the engine, a valve disposed in said conduit means for metering the quantity of fuel supplied to said cylinder, a device for controlling said valve, conduit means connecting said valve control device with said venturi to actuate said device in accordance with the mass of air flowing through said venturi, a valve device disposed in said conduit means intermediate the metering valve and cylinders for interrupting the flow of fuel, said valve device comprising a solenoid, a throttle controlled switch and an engine speed responsive switch in series with each other and with said solenoid, said valve device blocking the flow of fuel through said conduit means when said switches are closed to energize the solenoid.

2. A fuel injection system for an internal combustion engine comprising an air induction passage, a venturi formed in said passage, a throttle valve in said induction passage posterior to said venturi, a source of fuel under pressure, conduit means communicating said fuel source with the cylinders of the engine, a valve disposed in said conduit means for metering the quantity of fuel supplied to said cylinder, a device for controlling said valve, conduit means connecting said valve control device with said venturi to actuate said device in accordance with the mass of air flowing through said venturi, a valve device disposed in said conduit means intermediate the metering valve and cylinders for interrupting the flow of fuel, said valve device comprising a solenoid, a throttle controlled switch and an engine speed responsive switch in series with each other and said solenoid, said valve device blocking the flow of fuel through said conduit means when said switches are closed to energize the solenoid, a passage for bypassing air around the throttle when closed during idling, a valve in said bypass passage, and temperature responsive means actuating the bypass valve to render the quantity of idle air inversely proportional to engine temperature.

3. A fuel injection system for an internal combustion engine comprising an air induction passage, a venturi formed in said passage, a throttle valve in said induction passage posterior to said venturi, a source of fuel under

pressure, conduit means communicating said fuel source with the cylinders of the engine, a valve disposed in said conduit means for metering the quantity of fuel supplied to said cylinder, a device for controlling said valve, conduit means connecting said valve control device with said

5 venturi to actuate said device in accordance with the mass of air flowing through said venturi, a valve device disposed in said conduit means intermediate the metering valve and cylinders for interrupting the flow of fuel, said 10 valve device comprising a solenoid, a throttle controlled switch and a speed responsive switch in series with each other and said solenoid, said valve device blocking the flow of fuel through said conduit means when said switches are closed to energize the solenoid, a passage for bypassing air around the throttle when closed during idling, a valve in said bypass passage, a conduit communicating said control device with the induction passage 15 posteriorly of the throttle valve, valve means in said latter conduit for modulating the manifold vacuum acting on the control device, and engine temperature responsive means operatively connected to the bypass valve and the valve means to render the flow through both inversely proportional to engine temperature.

4. A fuel injection system as set forth in claim 1 in 20 which said valve device includes an armature having a valve element formed thereon, said armature and element being responsive to the fuel pressure and normally held thereby in a position permitting the free flow of fuel through the conduit means.

5. A fuel injection system for an internal combustion engine comprising an air induction passage; a venturi formed in said passage; a throttle valve in said induction passage posterior to said venturi; a source of fuel under pressure; conduit means communicating said fuel source with the cylinders of the engine; a valve disposed in said conduit means for metering the quantity of fuel supplied to said cylinder; a diaphragm device for controlling the metering valve, a conduit connecting said diaphragm device with said venturi for controlling said valve in accordance with the mass of air flowing through the venturi; a fuel distributor; said conduit means including a passage connecting the metering valve with said fuel distributor for delivering fuel to the distributor, and a plurality of passages leading from said distributor, said passages respectively communicating with the individual cylinders of said engine; a chamber in said manifold communicating with said delivery passage and said plurality of passages, valve means in said chamber adapted to cut off the flow of fuel through said manifold, said valve being responsive to the pressure of the fuel flowing through said distributor and normally moved thereby to a position permitting uninterrupted fuel flow to the passages, solenoid means adapted when energized to shift said valve to a position blocking the flow of fuel through the manifold, a source of power for energizing said solenoid, a throttle 30 actuated switch and an engine speed responsive switch connected in series with said power source and solenoid, said switches being adapted to energize said solenoid during throttle-closed deceleration of said vehicle.

6. A fuel injection system for an internal combustion engine as set forth in claim 5 in which said solenoid includes an armature operatively connected to the valve means, said armature having a surface exposed to the fuel pressure in said chamber for moving the valve means to permit the flow of fuel through the distributor.
